US00D865119S

(12) **United States Design Patent** (10) **Patent No.:** **US D865,119 S**
(45) **Date of Patent:** ** *Oct. 29, 2019

(54) **WATER PURIFYING FILTER FOR
REFRIGERATOR**

(71) Applicant: **LG Electronics Inc.**, Seoul (KR)

(72) Inventors: **Siyeon An**, Seoul (KR); **Jimin You**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/677,017**

(22) Filed: **Jan. 16, 2019**

Related U.S. Application Data

(63) Continuation of application No. 29/641,956, filed on Mar. 26, 2018, which is a continuation of application No. 35/502,657, filed on Sep. 23, 2016 (U.S. filing date under 35 U.S.C. 384), and having an international filing date of Sep. 23, 2016, now Pat. No. Des. 820,948.

(30) **Foreign Application Priority Data**

Apr. 12, 2016 (KR) 30-2016-0017281

(57) **CLAIM**

The ornamental design for a water purifying filter for refrigerator, as shown and described.

DESCRIPTION

FIG. 1 is a perspective view of a water purifying filter for refrigerator showing our new design:

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

(Continued)

The broken lines show portions of the water purifying filter for refrigerator that form no part of the claimed design.

1 Claim, 6 Drawing Sheets
